UNITED STATES PATENT OFFICE.

ISAAC VAN MITCHELL, OF LOS ANGELES, CALIFORNIA.

CARBURETER.

1,259,037.

Specification of Letters Patent. Patented Mar. 12, 1918.

Application filed February 10, 1915. Serial No. 7,393.

To all whom it may concern:

Be it known that I, ISAAC VAN MITCHELL, a citizen of the United States, residing in Los Angeles, in the county of Los Angeles and State of California, have invented new and useful Improvements in Carbureters, of which the following is a specification.

This invention relates to carbureters for internal combustion motors, and it has for its object to provide an improved carbureter which will be generally superior in point of relative simplicity and inexpensiveness of construction and organization, taken in connection with adaptability to varying conditions of use and service, effectiveness in operation, facility in control and durability and which will be generally superior under a wide range of varying working conditions.

The invention consists in the novel and useful formation, construction, combination, association and relative arrangement of parts, members and features, as hereinafter described, shown in the drawing and finally pointed out in claims.

25 In the drawing:

Figure 1 is a central, vertical, sectional view of an improved carbureter, organized to embody the invention, same being shown as applied to the manifold or fuel intake pipe of the motor; parts being broken away and parts shown in elevation for fullness of illustration.

Fig. 2 is a side elevation of the carbureter looking in the direction of the arrow "Fig. 2" in Fig. 1, parts being likewise broken away for fullness of illustration;

Fig. 3 is a detail transverse sectional view taken upon the line X²—X², Fig. 1, and looking in the direction of the arrow "Fig. 3," Fig. 1, and

Fig. 4 is a fragmentary plan view of a portion of the showing in Fig. 1.

Corresponding parts of all the figures are designated by the same reference characters.

45 Referring with particularity to the drawing, the improved carbureter therein disclosed is shown in Fig. 1 as applied to one end of the manifold intake pipe A for supply of fuel to the motor, the carbureter and 50 the manifold pipe being provided with matched flanges 5 and 6 suitably bolted together as at 7, so that the carbureter may feed directly into the manifold pipe, under regulation of a throttle valve 7 provided at 55 the top of the carbureter and mounted upon an axle or shaft 8 with one end of which is

connected a crank arm 9 whereby the throttle valve may be controlled manually or otherwise.

The carbureter in the main comprises a 60 liquid or hydrocarbon fuel chamber a at the lower portion of the carbureter, above which is provided a mixture chamber b there being provided two converging air inlet passages c and d, which converge at the mixture chamber b, said passages c and d arranged obliquely upwardly over the top of the fuel chamber a. e designates a valve controlling the admission of air through the passage c, such passage being an auxiliary air passage 70 whereas the passage d constitutes the main air passage and likewise constitutes the passage whereby the mixture of air and vaporized fluid proceeds to the mixture chamber b. f designates means of operative connection 75 between the throttle valve 7 and the auxiliary air passage valve e; whereby as the throttle valve is operated the valve e is operated to any extent as predetermined by means of adjustable connections g incorporated in the means and operative connection f. h designates an adjustable fuel spray nozzle whereby liquid fuel taken from the fuel chamber a is inducted to the feed passage d, the adjustable nature of the same 80 permitting the amount of such liquid fuel admission to be predetermined. k designates a liquid fuel feed pipe supplying liquid fuel to the fuel chamber a at the bottom of the same through a duct 10 controlled by 85 a needle valve 11, such needle valve being controlled as to its position as by a float 12 and operative connections 1 between the float and the stem of the needle valve, all in accordance with standard or any preferred 90 practice.

In the formation and construction shown in the drawing, the needle valve is housed in a tubular bolt 13 fast to the base cap 14 of the carbureter and the fuel chamber a 100 thereof, and threaded into the crown 15 thereof as at 16 such bolt being laterally perforated or slotted as at 17 to permit inflow of liquid fuel from the interior of the hollow bolt to the fuel chamber.

105 The operative connections 1 are shown as consisting of intermediate pivoted fingers 17^a mounted between lugs 18 projecting from an adjustable ring or bushing 19 threaded upon the bolt 13; said fingers 17^a 110 at their inner ends taking onto a circumferential groove 19^a in the upper end of the

2

stem of the needle valve 11. The fingers 17^a are enlarged at their upper ends so as to follow the fall of the float 12, and to be immediately responsive to rise of the latter, 5 also lifting the needle valve as the float falls, thus permitting an increased flow of liquid fuel through the duct 10 through the fuel chamber *a*. The threaded connection of the ring 19 with the bolt 13 permits the normal position or elevation of the fingers 17^a to be varied, thus varying the level of the liquid fuel within the chamber *a* with respect to the cut off point of the duct 10; all to the end that a proper level of liquid fuel may 10 be maintained within the chamber *a* and consequently properly supply the adjustable spray nozzle device *h*. The device *h* comprises, as shown, a hollow screw 20 threaded into the enlarged side wall of the chamber *a*, and carrying a nozzle body 22 which is provided with an enlarged end or hub 22^a surrounding the shank of the screw 20 immediately beneath the head 22^b thereof, such nozzle resting against the bottom 15 wall of the air passage *d* and being adjustable thereon as to variation and inclination; said nozzle being provided with a plurality of upwardly directed ducts 22^c through which fuel from the fuel chamber *a* is transmitted in the form of spray into the passage *d*, therein to be mixed with air and carried upwardly to the mixture chamber *b*. The tubular screw 20 is provided with a port 22^d communicating with the hub or 20 enlargement 22^a of the nozzle 22, thus establishing communication between the latter and the tubular screw and the fuel chamber *a*. A portion of the wall of the passage *d* is severed to constitute a detachable cap 25 held to the passage structure by screws 24, and permitting, upon removal, the introduction of a screw driver or other suitable implement within the passage *d* for manipulation of the screw head 22^b and the 30 adjustment of the nozzle 22. When the screw 20 is home the nozzle 22 is held in position of adjustment.

The valve *e* is mounted upon a shaft or axle 25 bridging the auxiliary air passage *c*, adjacent to the intake end thereof and an arm 26 fast to said shaft 25 carries a threaded adjusting screw 27 upon which is mounted a follower or threaded block 28 from which extends a link 29 which is pivotally connected therewith and with an arm 30 fixed to the shaft or axle 8 of the throttle valve 7. The arm 26 and these connections are exterior to the air passage *c*, and the adjusting screw 27 is provided with a finger- 35 ing feature 30 whereby the follower 28 may be adjusted to cause the same to travel to and from the axis of the shaft 25, to the end that said shaft may be rocked to a greater or lesser degree responsive to a certain oscillation of the shaft 8 and the throttle valve 40 45

7, all to the end that a greater or lesser responsive movement of the valve *e* may ensue and a greater or lesser amount of air be admitted to the mixture chamber *b* through the auxiliary air passage *c*. The normal position of the valve *e* may be determined and maintained by swinging the shaft 25 with the valve in the bearings of the shaft, and then fixing the position of same by means of a set screw 31 applied to such shaft and 50 mounted in the inner end of the arm 26. The adjustable connections *g* thus permitting control of the swing of the valve *e* and the set screw 31 permits the normal position of the valve *e* to be varied.

The operation, method of use and advantages of the improved carburetor constituting the invention will be readily understood from the foregoing description taken in connection with the accompanying drawing and the following statement:

Fuel from the chamber *a* is jetted into the passage *d* through the perforated nozzle 22 due to the partial vacuum formed in the passage *d* by engine suction, the flow of such fluid being dependent upon the inclination of the nozzle 22 under adjustment permitted by adjustment of the screw 20. The fuel thus drawn into the passage *d* volatilizes and mixes with the air in that passage and 90 the mixture proceeds to the mixture chamber *b* whence it is drawn past the throttle valve 7 into the manifold. An auxiliary supply of air is furnished through the passage *c* to impoverish the mixture in the 100 chamber *b*, subject to control by the valve *e* which is responsive to the movement of the throttle valve 7. The adjustment of the nozzle 22 is made to provide the proper feed of fuel in accordance with the demands of 105 the motors. This nozzle is held substantially at the level of the liquid fuel in the chamber *a* and is adjusted relative to such level.

The provision of a plurality of orifices 110 22^c through which the fuel is jetted into the passage *d* insures a good distribution of the liquid fuel throughout the incoming air, as well as increasing the range of adjustment of proportions of fuel to air when adjustment of the nozzle from the horizontal is made.

These satisfactory features of the carburetor permit of producing exactly the proper mixture of the proper richness for 115 supplying the needs of the motor and as the needs of such motor vary; the entire voluntary control being effected through the throttle valve.

Having thus disclosed my invention, I claim and desire to secure by Letters Patent:

1. In a carburetor, a fuel chamber, an air passage, and a fuel nozzle in the air passage and communicating with the fuel chamber; said fuel nozzle being adjustably 1

mounted whereby the feed of fuel therethrough may be varied; said nozzle being pivotally mounted in the air passage, and provided with a spray duct, the position of 5 which in the passage is shifted upon pivotal movement of the nozzle and independently of any throttle valve or engine movement.

2. A carbureter having a fuel chamber 10 and an inclined air passage, a fuel nozzle in the air passage and communicating with the fuel chamber; said fuel nozzle being adjustably pivotally mounted whereby the feed

of fuel therethrough may be varied independently of any throttle valve or engine 15 movement and in predetermined amount; said fuel nozzle having a plurality of orifices through which liquid fuel may be jetted into the air passage.

In testimony whereof, I have signed my 20 name to this specification in the presence of the two subscribing witnesses.

ISAAC VAN MITCHELL.
